EDUCATIONAL GAME PLAYING DEVICE

Wilford P. Johnson, 2919 SE. 78th Ave., Portland, Oreg.

Filed Oct. 20, 1961, Ser. No. 67,184

Term of patent 14 years

(Cl. D34—5)

Fig. 3

Fig. 2

Fig. 1

Fig. 4

Fig. 5

Fig. 6

FIG. 1 is a top plan view showing one end of the educational game playing device;

FIGS. 2, 3, 4 and 5 are side elevational views of the educational game playing device, each view being taken at ninety degrees from the other views; and

FIG. 6 is a bottom plan view of the educational game playing device showing the opposite end from that of FIG. 1.

I claim:

The ornamental design for an educational game playing device, as shown.
